DECORATOR CANOPY BED TOP FRAME
Clarence J. Desneux, Clearwater, Fla., assignor to
Desneux Tool and Die Company, Clearwater, Fla.
Filed Jan. 7, 1965, Ser. No. 423,987
5 Claims. (Cl. 5—362)

This invention relates to frames of various kinds and materials, to the nature and character of said frames, and to the manner in which individual parts are assembled and fastened together, as well as to structures supported by and constituting an assembly with such frames.

The invention relates particularly to frames for supporting objects such as decorative canopies over beds, the specific nature and character of such frames as well as the manner in which the parts can be readily erected, fastened together, moved, and taken down.

Various types of frames have been provided of many shapes and sizes with the parts fastened together in various ways. Prior frames have not been satisfactory due to their weight, bulkiness, the manner in which the parts were fastened together, difficulty of erection, and lack of durability.

It is an object of the invention to provide a frame which could be of any desired size although of relatively small bulk, and light weight, and particularly suitable for use as a decorative canopy bed top frame, as well as a frame having an upper portion with legs connected thereto and supporting the same, which can be readily erected and taken down by inexperienced persons without special tools or equipment.

Another object of the invention is to provide unique means for fastening together the parts of a frame square in cross section including spring clamps which removably interlock with one member and extend around and hold another, and with the parts in assembled relation, by a retaining arm and with cross bars on parallel sides of the frame members having their ends journaled in plastic inserts.

Other objects and advantages of the invention will be apparent from the following description taken in conjunction with the accompanying drawing in which:

FIG. 1 is a perspective of the bed with a decorator canopy frame in accordance with the present invention over the same;

FIG. 2, an enlarged fragmentary view illustrating one of the connectors;

FIG. 3, an exploded view of one of the connections;

FIG. 4, an enlarged fragmentary section on the line 4—4 of FIG. 2;

FIG. 5, a section on line 5—5 of FIG. 2; and,

FIG. 6, a perspective of the fastening clip itself.

Briefly stated the present invention is a frame composed of multiple parts including a top portion having spaced sides supported by legs with the sides of the top portions and the legs spanned by cross bars which are connected to the sides and the legs by means of novel plastic inserts which provide tight joints. The side members and the legs are fastened together by pairs of spring clamps one of each pair having a head connected by a neck to the flat body of the clamp which head is inserted through a slot in one of the members to be connected and with the clamp extending around and having its opposite end offset toward the other clamp with relatively small transversely curved extensions which when those of the pair are combined form a stud which can be received in an opening in an ornamental device such as a knob, the two clamp members extending on opposite sides of a member to be connected to the first.

With continued reference to the drawing a top frame is provided in the form of a pair of generally parallel tubu-

2

lar side members 10 having arched or upwardly bowed intermediate portions 11. The tubular top side members 10 preferably are of square cross-section with connecting cross bars 12. Five cross bars have been found to be an appropriate number, one connecting the bowed portions of the side members with the other two adjacent the ends thereof.

A unique manner of joining the cross bars and side members includes the provision at the joint of circular concentric openings 13 and 14 in the facing and remote portions of the side members 10 and the insertion of a plastic insert 15 having a closed end 16 with a central knob 17 which fits into the opening 14. The interior of the insert is of uniform diameter but the exterior 18 tapers from its closed end outwardly to a reduced portion 19 where a shoulder 20 is formed. When the insert is applied it is forced in place until the shoulder 20 is located within the tube and against the interior wall of the member 10 so that it cannot be readily removed. The insert preferably is of plastic, for example nylon, and when the end of the cross bar 12 is received therein it provides a relatively tight joint due to the gripping of the plastic about the smooth surface of the cross bar.

The top frame is supported by legs 21 connected by cross bars 22 identical with the cross bars 12, such cross bars preferably being of tubular material such as aluminum or chrome steel. Inserts 15 are employed like those in the connection between the cross bars of the top frame members. While only a single cross bar is illustrated connecting each pair of legs, it will be apparent that if desired additional cross bars can be employed in fastening the legs of each pair together.

The legs or corner posts which support the top frame are connected to the top frame in a novel manner. This includes the provision of slots 23 in the near and remote sides of each pair of legs, the legs having squared ends over which extend the top frame members 10. In order to secure the top frame members on the leg, spring clamps 24 are provided each having an angular extremity or head portion 25 connected by a small neck 26 to the main flat body portion of the spring clamp 24. The opposite end of the spring clamp from the head 25 is provided with gently curved portions 27 and 28 which are connected by a relatively straight portion 29 and the curved portion 28 terminates in a reduced curved extension or end portion 30. The end portions 30 form reduced extensions of the longitudinal axis of the post 21 and when two spring clamps 24 are applied over opposite sides of the upper frame member 10 the extensions form in effect a stud receivable within an opening 31 of a finial or decorative knob 32. The spring clamps are such that the extensions 30 normally are urged apart, consequently there is a gripping or binding action on the member 32.

It will be apparent from the foregoing that a frame is provided of simple inexpensive construction, of light weight and minimum bulk which can be readily installed or removed and which will provide a relatively rigid structure and when not erected will occupy a relatively small package for storage and shipment.

Further it will be understood that in the erection of the device the two bowed side members of the top frame are placed in parallel side-by-side relation with the larger of the openings 13 and 14 facing each other, whereupon the inserts 15 are forced in place and the five cross bars 12 are inserted making a substantially rectangular frame. Thereafter a pair of legs is placed beneath the side members 10 in spaced parallel relation with the large openings 13 facing each other, after which the inserts 15 are installed and then the cross bars 22. Then one end of the rectangular top frame is raised and a pair of legs placed under one end of same so that the side members

10 rest thereon, after which the spring clamps 24 are applied to fasten the sides of the top frame to the leg and the decorative element is applied to the spring clamps over each leg. After the legs are applied at one end they are applied at the opposite end in a like manner.

It will, of course, be understood that the frame of the present invention is adapted to be placed over a bed 33 of conventional construction.

It will be obvious to one skilled in the art that various changes may be made in the invention without departing from the spirit and scope thereof and therefore the invention is not limited by that which is illustrated in the drawing and described in the specification, but only as indicated in the accompanying claims.

What is claimed is:

1. A decorator canopy bed top frame comprising spaced generally parallel upwardly arched tubular members of generally square cross section, cross bars connecting said tubular members with one cross bar adjacent each of the ends of the tubular members, one adjacent each end of the arched portions thereof, and another connecting the intermediate portions of the arched tubular members, said spaced tubular members and connecting bars defining a generally rectangular structure, said tubular members having openings in which the end portions of the cross bars are received and having smaller concentric openings in the remote sides of the tubular members, a plastic insert located in the openings of said tubular members and about the ends of said bars, said plastic insert having a substantially cylindrical internal wall with one end of the cylinder closed and with a central projection extending into the opening in the remote wall, and with the external wall of said insert enlarged from said closed end to a location near the opposite end of the insert and providing a shoulder against the inside wall of the tube and preventing ready removal of the insert, a pair of legs supporting each end of said tubular members, means connecting said legs and tubular members comprising a pair of spring clamps having relatively flat body portions with inwardly and angularly disposed portions and a connecting neck of less width at one end than at the other end, the metal curving to a position at right angles to the body of the clamp and then curving gently to a position substantially 90° and provided with a reduced central lengthwise extension curved from edge to edge so that when the extensions of two clamps are placed together it will have a generally rounded configuration, the angular end of said clamp being of a width to be freely received within the tubular members, and the extensions being disposed in an upright position to be received and held within an opening in a decorator member.

2. A decorator canopy bed top frame comprising spaced generally parallel upwardly arched tubular members having flat sides, bars connecting the end and arched portions of said tubular members, said tubular members having openings in which the end portions of said bars are received and smaller concentric openings opposite the openings in which said bars are received, a plastic insert located in the openings in said tubular members around the ends of said bars, legs of tubular construction and of a size near that of said tubular members supporting said tubular members adjacent the ends thereof, spaced end openings in the lower ends of said legs, a plastic insert in each of said openings, a bar having its extremities in said inserts, the upper ends of said legs having slots at opposite sides of said tubular members, means connecting the upper ends of said legs and said tubular members, said means comprising a pair of spring clamps having narrow necks and enlarged heads with said heads extending into the slots and the legs, two of such spring clamps being disposed one at each of the opposite sides of said tubular members, said spring clamps having inwardly disposed offset portions

and generally parallel extensions to receive a combination decorator knob and retainer.

3. A decorator canopy bed top frame comprising spaced generally parallel upwardly arched tubular members of generally square cross section, cross bars connecting said tubular members with one cross bar adjacent each of the ends of the tubular members, one adjacent each end of the arched portions thereof, and another connecting the intermediate portions of the arched tubular members, said spaced tubular members and connecting bars defining a generally rectangular structure, said tubular members having openings in which the end portions of the cross bars are received and having smaller concentric openings in the remote sides of the tubular members, a plastic insert located in the openings of said tubular members and about the ends of said bars, said plastic insert having a substantially cylindrical internal wall with one end of the cylinder closed and with a central projection extending into the opening in the remote wall, and with the external wall of said insert enlarged from said closed end to a location near the opposite end of the insert and providing a shoulder against the inside wall of the tubular member and preventing ready removal of the insert.

4. A canopy frame structure of the character described comprising spaced tubular top frame members of substantially rectangular cross-section,

spaced tubular leg members of substantially rectangular cross-section abuttingly supporting said top frame members, cross bar members extending between and connecting respectively said top frame members and said supporting leg members together, fastener means fixedly connecting said top frame members and said leg members together, said fastener means comprising opposed spring clamps having integral angular anchoring head means at one end thereof interlockingly engaging with apertured opposite side portions of one of said leg members adjacent one end thereof and clamping portions which extend around an adjacent top frame member for frictional engagement therewith, said opposed spring clamps having longitudinally extending projections at the opposite ends thereof, decorator holding cap means for mounting on and receiving said clamp extensions whereby when said opposed clamp sections are drawn into frictional holding relation with said top frame member and said cap means is positioned in holding relation with said opposed clamp extensions, the latter fixedly secures said top frame member and said leg member together.

5. In a frame structure having at least a portion thereof composed of tubular members of generally square cross-section held together by a clamp structure, said clamp structure comprising

a pair of facing metal spring clamp members having relatively flat parallel body portions with inwardly and angularly disposed portions at one end thereof with connecting neck portions of reduced width, the metal of each clamp member intermediate its ends curving toward the other clamp member to a position at right angles to the body of the clamp member and then curving gently to a position substantially 90 degrees thereto to provide a central lengthwise extension of reduced width curved from edge to edge so that when the extensions of the two clamps are placed together they will have a generally cylindrical configuration,

the angular ends of said clamp members being of a width adapted to be freely received for latching engagement in opposite wall openings of one of the tubular members, and a decorator member having a tubular bore for receiving said extensions and securing them in their

generally cylindrical configuration to maintain the spring clamp members in clamping position about another tubular member.
